UNITED STATES PATENT OFFICE

EUGENE C. HERTEL, OF CHICAGO, ILLINOIS, ASSIGNOR TO SINCLAIR REFINING COMPANY, OF NEW YORK, N. Y., A CORPORATION OF MAINE

METHOD OF SEALING CONTAINERS IN THE ART OF CRACKING HYDROCARBONS

No Drawing.

Application filed March 7, 1929. Serial No. 344,940.

This invention relates to improvements in the operation of apparatus for the coking of heavy oils, such as crudes, topped crudes, flux oils, other residual oils and the like. More particularly, this invention relates to improvements in making a light joint in apparatus for carrying out such coking operations in which a charge of coke is formed and deposited within a coking receptacle from which this coke product must be discharged. Commercially, lump coke is more valuable than coke fines. The improvements of this invention assist particularly in increasing the production of lump coke and in decreasing the production of coke fines in such coking operations. Other advantages of the invention will be apparent as the description proceeds.

The invention is particularly useful in connection with the operations described in applications Serial No. 340,996 filed Feb. 18, 1929 and Serial No. 341,214 filed Feb. 19, 1929 by Harry L. Pelzer and Serial No. 347,533 filed Mar. 16, 1929 by Edward W. Isom and George H. Taber, Jr., but, as will be apparent, it is of more general application.

Most of the fines produced in such coking operations are produced, not during the coking operation proper, but during the discharge of the coke product from the coking receptacle, and such fines are produced by the disintegration of what otherwise would be lump coke. This discharge of the coke product has been effected, heretofore, in a number of ways ranging from the crude digging out of the coke product to more refined methods involving the rearrangement of chains or cables within the coking receptacle so that, at the termination of the coking operation proper, the chains or cables extend through the body of the coke charge so that the coke product can be broken up within the receptacle and discharged by pulling out the chains or cables.

In applications Serial No. 344,952 filed Mar. 7, 1929, by Oliver F. Campbell and Eugene C. HerTEL and Serial No. 345,016 filed Mar. 7, 1929, by Willis S. GULLETTE, there are described advantageous methods

of discharging the coke product of such coking operations from the coking receptacle involving, in one aspect, the provision of cylindrical coking receptacles having heads substantially the full diameter of the coking receptacle. This invention relates particularly to an improved method of making tight such large-diameter heads, that is heads upwards of 5' in diameter. The invention is of special value in connection with the operations described in these applications, but, as will be apparent, it is of more general application.

According to this invention, when the coking receptacle is ready to be closed, a gasket consisting of a rope of heat-resistant fibrous material, such as asbestos, saturated with an organic substance decomposing at a temperature short of about 900° F. to leave a carbonaceous residue, such as molasses, glue, petroleum tars or coal tars, rubber, etc., is put in place between the large-diameter head and its seat on the coking receptacle, the head is clamped in place and then, as the coking receptacle is heated to operating temperature, say 950-1100° F., the organic saturant of the gasket rope carbonizes forming a tight joint between the head and the coking receptacle. Where the head is seated on the lower side of the coking receptacle, sufficient petroleum tar or other residual petroleum stock to submerge the joint between the head and the coking receptacle may, with advantage, also be supplied to the coking receptacle after the head is clamped in place and before the heating operation is started. If a liquid saturant of sufficiently low viscosity is used, it may be applied directly to the gasket rope. If a liquid saturant of higher viscosity is used, it may be applied to the gasket rope dissolved in or diluted with some volatile solvent. If a solid or semi-solid saturant is used, rubber for example, it may be applied to the gasket rope dissolved in some volatile solvent.

The invention is of special value in connection with the operations described in applications Serial Nos. 344,952 and 345,016 mentioned above. In carrying out such operations on a commercial scale, it is ad-

vantageous to use large coking receptacles. A coking receptacle 9' in diameter and 30' high, for example, would require the tight sealing of a head 9' in diameter; it is extremely difficult to make a vapor-tight joint between a head of such diameter and the coking receptacle with the best available mechanical structure. This invention, however, provides a simple method of making 10 tight such large-diameter heads, and also requires but simple mechanical structure.

I claim:

1. An improved method of making a tight joint between heads upwards of five feet in 15 diameter and receptacles containing heavy hydrocarbon oils in which said oils are reduced to coke which comprises placing a gasket consisting of a rope of heat-resisting fibrous material having the general properties 20 of asbestos which is saturated with an organic substance which is at least in a liquid state and which decomposes at a carbonizable temperature short of 900° F. to leave a carbonaceous residue between the 25 head and its seat on the coking receptacle, clamping the head in place and then heating the coking receptacle to an operating temperature exceeding 900° F.
2. An improved method of making a tight 30 joint between heads upwards of five feet in diameter and receptacles containing heavy hydrocarbon oils in which said oils are reduced to coke which comprises placing a gasket consisting of a rope of heat-resisting 35 fibrous material having the general properties of asbestos which is saturated with an organic substance which is at least in a liquid state and which decomposes at a carbonizable temperature short of 900° F. to leave a carbonaceous residue between the head and its 40 seat on the coking receptacle, clamping the head in place, submerging the joint between the head and the coking receptacle beneath a petroleum residue and then heating the 45 coking receptacle to an operating temperature exceeding 900° F.

In testimony whereof I affix my signature.

EUGENE C. HERTHEL.
